Primary Examiner—Sandra L. Morris

[57] **CLAIM**

The ornamental design for a board game, as shown and described.

DESCRIPTION

FIG. 1 is a top plan view of the merry mixup board game, showing my new design, showing the top left section of the game, shown separately for ease of illustration;

FIG. 2 is a top plan view thereof, showing the top right section of the game;

FIG. 3 is a top plan view thereof, showing the bottom left section of the game;

FIG. 4 is a top plan view thereof, showing the bottom right section of the game;

FIG. 5 is a reduced top plan view thereof, showing the complete game board; and,

FIG. 6 is a top plan view of a game piece.
